UNITED STATES PATENT OFFICE.

MELVIN L. SEVERY, OF LOS ANGELES, CALIFORNIA.

SYNCHRONIZER.

1,356,226.

Specification of Letters Patent. Patented Oct. 19, 1920.

Application filed May 7, 1917. Serial No. 166,969.

To all whom it may concern:

Be it known that I, MELVIN L. SEVERY, a citizen of the United States, residing at Los Angeles, in the county of Los Angeles and State of California, have invented certain new and useful Improvements in Synchronizers, of which the following is a specification.

This invention relates to devices for synchronizing the rotary movements of two independently driven and distant shafts.

In my Patent No. 1,186,851 granted June 13th, 1916, I describe and claim a device capable of producing such close speed regulation of a driven member as to permit accurate synchronization of electric impulses, produced by a commutator carried by said driven member, with the periodic vibrations of a sonorous body such as a tuned string. In various devices too numerous to mention it is necessary to drive independently two separate shafts not only at the same or approximately the same rotative speeds but in a definite and maintained phase relation, and the present invention involves certain additions to and refinements upon the device of my prior patent to adapt it to use in this last-named field.

I accomplish the result by making use of two of the devices of my prior patent which are initially adjusted to practically equal speeds. One of these is known as the master device and differs from the mechanism described in my prior patent only in the inclusion of a feature designed to compensate for temperature variations. The second of the two mechanisms, which I call the controlled device, is the same as the first with the following additions:

1. An electromagnetic means for varying the speed adjustment while the device is in operation;

2. Manually-operable means for effecting an absolute adjustment of the driven element with reference to the driven shaft for the purpose of adjusting the phase of the driven element with reference to that of the driven element of the first device; and

3. An electromagnetic mechanism for determining when the master and controlled devices are in the desired phase, and for thereafter maintaining them closely in phase by adjusting the speed of the controlled device.

A preferred embodiment of the inven-

tion as outlined above is illustrated in the accompanying drawings, in which:

Figure 1 is a plan view of the complete mechanism with the electric circuits shown in diagram;

Fig. 2 is a horizontal axial section of the controlled device, certain wiring connections being shown in diagram;

Fig. 3 is an enlarged sectional view showing a centrifugal contact and the electromagnetic means for adjusting same;

Fig. 4 is a view of the electromagnetic adjusting means of Fig. 3, viewed from the left in that figure;

Fig. 5 is a diagram of the speed-controlling circuit characteristic of the device of my patent above referred to, one such circuit forming a part of the master device and another identical circuit forming a part of the controlled device; and

Fig. 6 is a wiring diagram showing the connections for indicating and maintaining synchronism between the master and the controlled devices. This circuit is wholly independent of the speed-control circuits shown in Fig. 5.

The speed-control mechanism.—As previously stated, this mechanism is substantially that of my prior patent and is described here in order that the additions and improvements hereinafter described may be fully understood. The two mechanisms are substantially identical and all the added features are included in the driven element, so that a description of that element will suffice for both.

Two motors or other prime movers 11 and 12 are used, the motor 11 driving the master device or instrument and the motor 12 the controlled device. The motor 11 drives a metallic annulus 13 preferably of copper, and the motor 12 drives a similar copper annulus 14. In each case the driven element whose speed is to be maintained constant consists of an annular shell indicated by the numerals 15 and 16 in Fig. 1. The internal construction of these is the same and may be determined from an inspection of Fig. 2. In Fig. 2, the shell 16 is provided with an annular series of electromagnets 17, two pairs being shown in this figure. The shell 16 is likewise provided with two slip rings 18 and 19 insulated from said shell and from each other, and bearing on these slip rings are properly

insulated brushes 20 and 21. The shell 16 also carries a very light spring switch, the arm of which is indicated by the numeral 22, this switch contacting with an appropriate contact 23 (see Fig. 3). The switch arm 22 is pivoted at 24 so as to be adjustable by a threaded stem or screw 25, which bears not against the arm 22 but against a bi-metallic thermostatic bar 26 rigidly connected to the support on which the switch arm 22 is mounted. The screw 25 permits such adjustment of the switch 22 as to determine the rotative speed of the shell or member 16 at which the switch 22 will be brought into touch with the contact 23. The bi-metallic bar 26 is so designed as to compensate or approximately compensate for the disturbing effects which are otherwise induced by changes of temperature. Variations in temperature such as may be caused by changes in room temperature, or by the heating effect of eddy currents induced in the shells 13 or 14, affect in some degree the speed regulative action of the device, and the thermostatic bar 26 is so designed as to compensate or approximately compensate for the disturbing effect mentioned.

In Figs. 3 and 4 an electromagnetically operated ratchet device is shown for adjusting the screw 25. This mechanism in the example shown is used only on the controlled device, and as it forms part of the adjusting circuit will be described hereafter. It is to be understood that this electromagnetic adjusting mechanism is ordinarily not used on the master device, *i. e.* on member 15, but that on this member the screw 25 is manually adjustable by means of a wheel 27 indicated in Fig. 1. I do not, however, mean to disclaim its use in cases where its function can be utilized; for example, to make adjustments when necessary.

The windings of the magnet 17 are connected in series with each other by means of a wire 28, and one end of this circuit is grounded to the shell 16. The other end is connected to the slip ring 19. Similarly, the spring switch arm 22 is grounded to the member 16 and the insulated contact 23 is connected to the slip ring 18. These connections are fully shown in diagram in Fig. 5, and may also be traced out in Figs. 1, and 2 so far as the parts are shown in the respective figures. The brush 20 which runs on the slip ring 18 is connected directly to one end of a resistance 29 whose opposite end is connected through a battery 30 to ground, ground being made by connecting the terminal of the battery to a bearing of the machine as indicated at 31 in both Figs. 1 and 5. The brush 21 which runs on the slip ring 19 is connected to one end of a resistance 32 whose other end is

connected with the circuit between the resistance 29 and the battery 30.

A shunt circuit for cutting out the resistance 32 is made by means of the wires 33 and 34, and is controlled by a switch arm 35 urged open by a spring 36 but at times held closed by an electromagnet 37 which is included in a shunt or bridge connection leading from a point between the brush 20 and resistance 29 to a point between the battery 30 and the ground connection at 31. This circuit is duplicated, one being present in the master device and the other in the controlled device, and the circuits are shown on a small scale in Fig. 1.

When the driven member of either device is below the speed for which it is adjusted, the spring switch arm 22 is out of touch with the contact 23. A circuit then exists from the battery 30 through the resistance 29 and magnet 37 which closes the switch 35 and shunts the resistance 32 out of circuit. When the switch 35 is closed current will freely flow from the battery 30 through the wire 34, switch 35, wire 33, brush 21 and slip ring 19 to and through the windings of the magnets 17, and thence through the ground connections back to the battery. The resistance 32 being shunted out of the circuit, a comparatively heavy current will flow and a comparatively heavy torque will be exerted between the copper annulus 13 (referring now to the master device) and the magnets 17 of its corresponding driven member. This will produce an increase in the rotative speed of such driven member, and when this speed is sufficient to cause the switch arm 22 to close against the contact 23 the circuit closed through ground will form a shunt around magnet 37 and will so weaken this as to cause switch 25 to open.

As soon as this occurs all the current flowing to the magnets 17 must flow through the resistance 32. The field of the magnets 17 is thereby correspondingly weakened, and the driving torque between the annulus 13 and the magnet 17 co-acting therewith is reduced.

As pointed out in my prior patent, when the device is in operation the centrifugal switch-arm 22 has a periodic or intermittent action resulting in a periodic or intermittent action of the magnet relay switch 35, and such action adjusts itself with such nicety as to produce a practically constant speed of the driven elements 15 and 16 regardless of minor speed variations of their respective driving motors 11 and 12, and regardless of slight changes of load. Where only one device is involved, the speed regulation is amply close for all ordinary purposes. When two are involved even a very slight difference in rotative speed would, in the course of time, involve a cumulative error result-

ing in marked phase difference, objectionable for certain classes of work. To adapt my device for this purpose, and remembering that the absolute speed of either instrument considered alone is sufficiently uniform, I am enabled to adopt one permanently adjusted instrument as a standard or master instrument, and then modify the other by the addition of means to effect a minute and progressive adjustment thereof to preserve its phase relation to the master instrument.

Phase-finding mechanism.—The member 15, which is the driven member of the master instrument, is rigidly connected to a wheel or the like, 38, which I have chosen to symbolize the driven member whose speed is maintained constant. What particular mechanism this may be is immaterial to the present invention. The driven member of the controlled device is represented by a disk or wheel 39. It is necessary not only that the disk 39 turn at the same speed as the disk 38, but also that it be brought into perfect phase relation with the disk 38 and maintained there. Assuming that the two devices can be started at perfectly equal speeds, and I am able to do this with devices such as shown in the drawings, it is still a fact that they will probably start out of phase, and some means must be provided for bringing them into phase after they have started.

Accordingly, in the controlled device the disk 39 is not rigidly attached to the driven member 16 but is swiveled thereto by means of a collar 40. The connection of member 16 and the disk 39 consists of a rod 41 axially slidabie in a tube 42, which tube is formed integral with the member 16. The rod 41 is provided with a longitudinal spline or feather connection 43 with the tube 42, and is further provided with quick pitch threads 44 which engage the disk 39. Consequently, the angular position of the disk 39 with reference to the member 16 may be adjusted by an axial shifting of the rod 41, and when the rod 41 is positively held in its adjusted position the member 16 and the disk 39 must turn together in the definite angular relation produced by such adjustment. In order to shift the rod 41 to effect the desired adjustment, I make use of a rod 45 having a swivel connection to a head 46 on the rod 41, the rod 45 being of square cross section and held against rotation by a square guideway 47. Swiveled on the end of the rod 45 is a threaded sleeve 48 turning in a fixed threaded block 49, and capable of being turned by a crank arm 50. The longitudinal adjustment of the rod 41 is thus effected at a slow progressive rate by turning the crank 50, and this adjustment may be made while the machine is rotating.

In order to indicate when the devices have been brought into phase by such adjustment, I provide the member 15, which as will be remembered is rigidly connected to the disk 38, with a single insulated contact 51 of small extent, and I provide the disk 39 with a similar contact 52. A brush 53 runs on the periphery of the member 15 in co-active relation with the contact 51, and a similar brush 54 runs on the periphery of the disk 39 in co-active relation with the contact 52. The brushes 53 and 54 are connected together by a wire 55^a which may be interrupted by a manually operable switch 55^b, and certain other connections hereinafter described give an electric impulse when the two brushes 53 and 54 contact with their respective contacts 51 and 52 at the same moment. This impulse is used to indicate that true phase relation has been initiated so that adjustment through the crank 50 will be stopped. It is also used to connect and render operative an automatic adjusting means for the controlled device.

Mechanism for adjusting speed of driven member while running.—The screw 25 of the driven member 16 of the controlled device is provided with a ratchet wheel 55. (See Figs. 2, 3 and 4.) Pivoted concentrically with the wheel 55 is an arm 56 held in its mid or neutral position by a leaf spring 57. Pivoted on the arm 56 is a double pawl 58 held in its neutral position in which it does not engage the ratchet wheel 55, by a spring 59. The spring 59 is much lighter than the spring 57. The double pawl 58 carries an armature 60 which swings between the pole pieces of two electromagnets 61 and 62. If either magnet is momentarily energized it attracts the armature 60, the initial movement overcoming the spring 59 and causing one or the other end of the double pawl 58 to engage the ratchet wheel 55. The further movement of the armature 60 swings the arm 56 against the resistance of the spring 57, and moves the ratchet wheel 55 the space of one tooth. Thus the actuation of the magnet 61 increases the speed at which the centrifugal switch 22 will act to close the circuit, and the actuation of the magnet 62 decreases the speed at which said switch 22 will close the circuit.

One terminal of each of the magnets 61 and 62 is connected by a wire 63 to a brush 64 which contacts with a slip ring 65 on the disk 39. The other terminal of the magnet 61 is connected by a wire 66 to a brush 67 which runs on a slip ring 68 concentric with the slip ring 65. The other terminal of the magnet 62 is connected by a wire 69 to a brush 70 which runs on a slip ring 71 concentric with and located between the slip rings 65 and 68. In Fig. 2 these con-

nections are traced out in diagram. The wires would, of course, be inclosed within the rotary member 16 and sleeve 42. The provision of the brushes 64, 67 and 70 is to 5 permit the relative rotary movement of the member 39 with reference to the member 16.

As already stated the member 39 is provided with an insulated contact 52 described 10 as intended for indicating when the correct phase relation has been attained. The remainder of the periphery of disk 39 is taken up with two other insulated contacts 72 and 73. (See Figs. 1 and 6.) The slip ring 68 is connected to the contact 73, and the slip ring 71 is connected to the contact 72. Consequently, the contact 72 is connected to that magnet which provides a retarding adjustment, and the contact 73 15 is connected to the magnet which produces an accelerating adjustment of the driven member of the controlled device. The third slip ring 65 is connected to a slip ring 74, and through a brush 75 and wire 76 to the 20 right-hand contact 77 of a relay switch hereinafter described. The contact 52 is connected to a slip ring 78, and from that by means of a brush 79 and wire 80 to one terminal of a relay magnet 81. The other 25 terminal of the magnet 81 is connected by a wire 82 to the left-hand contact 83 of the relay switch above mentioned.

This relay switch consists of the contacts 77 and 83, and an arm 84. (See Fig. 6.) The arm 84 is urged to the right by a spring 30 85, but in starting adjustment is latched to the left against contact 83 by means of a pivoted armature 86 which may be drawn to releasing position by the energization of 35 magnet 81. A spring 87 opposes the action of this magnet. The switch-arm 84 is connected by means of a wire 88 to one terminal of a battery 89 whose other terminal is connected to a brush 90 running on a slip ring 40 91 on the driven shaft of the master device, and electrically connected to the contact 51 heretofore mentioned.

Operations.—To start the devices into operation the first step is to open switch 55^b 45 and latch the arm 84 of the relay switch to the left by means of the armature 86, thus closing the contact at 83. The motors 11 and 12 are then started, it being assumed that the centrifugal switches 22 of the two 50 devices are so adjusted that their driven shafts will turn at approximately equal speeds. Such adjustment can be made by trial and error, and after the devices have been in operation this adjustment need not 55 be repeated because as soon as the mechanisms are shut down the entire regulating mechanism goes out of action, and leaves the devices in the condition and adjustment at 60 which they had been operating in practical synchronism.

With the two devices in operation at substantially equal speed it is now necessary to bring them into phase. Switch 55^b is closed. Then the crank 50 is turned thus causing the disk 39 to gain or lose with reference to 70 the rotary member 16 of the controlled device. Since the adjustment is relatively slow this adjustment plus whatever slight speed difference there may be between the two devices, will inevitably cause the brush 75 75 53 to be against the contact 51 at the moment that the brush 54 is against the contact 52. At such moment the devices are in the desired phase. The effect of this simultaneous contact of the two brushes 53 80 and 54 is to cause a current to pass from the battery 89 to the brush 90, slip ring 91, contact 51, brush 53, to the brush 54, and thence through contact 52, slip ring 78, brush 79 and wire 80 to the magnet 81. From the 85 other terminal of said magnet 81 it returns by way of wire 82, contact 83, switch arm 84, and wire 88 to the battery 89. The resulting attraction of the magnet 81 on the armature 86 unlatches the arm 84 and allows it to 90 move to the right under the influence of the spring 85, so that the arm 84 moves out of touch with contact 83 and into touch with contact 77. This immediately cuts magnet 81 and contact 52 out of circuit, and establishes a circuit from the battery 89 through switch-arm 84, contact 77, wire 76, brush 75, slip ring 74, slip ring 65, brush 64 and wire 63 to one terminal of each of the magnets 61 and 62. The other terminals of these 100 two magnets are respectively connected through the slip ring connections 67, 68, and 70, 71, to the contacts 73 and 72.

If the brush 54 is on the contact 72 at the moment that contact 51 reaches the brush 105 53, the controlled device has been gaining and must be retarded. This effect is secured because the contact 72 is connected to the retarding magnet 62, and the impulse sent through the line when the contact 51 reaches 110 the brush 53 actuates the adjusting device to cause the controlled device to drive at slightly slower speed. This adjustment will be repeated at each revolution until the brush 54 is on the contact 52 at the moment 115 that contact 51 reaches brush 53. Contact 52 is now dead through the action of the switch-arm 84.

Should the brush 54 be on the contact 73 at the moment the contact 51 reaches the 120 brush 53, then the controlled device has been losing with reference to the master device and a corresponding adjustment is made because the contact 73 is connected to the magnet 61 which will receive an impulse through this contact at the moment that the contact 51 reaches said brush 53. This will adjust the controlled device to turn faster, and thus the controlled device is given a slight tendency to hunt back to its 130

adjustment for synchronism should it depart from this adjustment in either direction.

Various other arrangements of the circuit and various modifications of the details of the adjusting mechanism will readily suggest themselves. The fundamental idea of the invention is the use of two speed-controlling devices, one of which is adjustable 10 while running, together with a phase-finding and retaining mechanism operatively related to the adjusting mechanism of the second or controlled device to adjust it toward its correct phase immediately upon its departure therefrom. In the accomplishment 15 of this desired function the provision of the thermostatic adjustment for the centrifugal switch is of the greatest importance, particularly as the two mechanisms may be 20 widely separated and may be subjected to thermal conditions which are different and which vary at different rates, and hence would otherwise introduce a serious disturbing factor.

It may frequently happen that the two instruments are widely separated, and as a consequence are subjected to temperature variations which differ widely for the two instruments. The provision of a thermostatic compensating device on each instrument to neutralize or approximately neutralize the disturbing effects of temperature, reduces the tendency of each instrument to depart from its constant speed operation, and consequently reduces the necessary corrective action of the phase-maintaining mechanism. A regulation that is sufficiently close for one instrument is not sufficiently close to maintain accurate phase 40 relation of two instruments. This makes necessary the phase-finding and maintaining mechanism characteristic of the present invention. The thermostatic device by eliminating the disturbing effects of temperature, relieves the phase-maintaining mechanism of considerable work.

Having thus described my invention, what I claim is:—

1. The combination with two speed controlling mechanisms, each including a driving member, a driven member, a variable ratio drive means interposed between said driving and driven members, and a speed responsive device subject to the speed of the driven member and operative to vary the driving ratio of said drive means; of reversible electrically actuated adjusting means for adjusting the action of one of said speed responsive devices while running; a rotary 50 commutating device having two contacts of considerable extent individually connected to said adjusting means to control reverse actuations thereof, and driven by one of said driven members; a second rotary commutating device having a single contact of small extent and driven by the other of said driven members; and electric connections connecting the adjusting means and the first 55 commutating device in circuit with the second commutating device, whereby the second commutating device actuates the adjusting means in a direction controlled by the first 60 commutating device according to the direction of phase displacement of the driven members.

small extent and driven by the other of said driven members; and electric connections connecting the adjusting means and the first commutating device in circuit with the second commutating device, whereby the second commutating device actuates the adjusting means in a direction controlled by the first commutating device according to the direction of phase displacement of the driven members. 70

2. The combination with two speed controlling mechanisms, each including a driving member, a driven member, a variable impositive drive means interposed between said members, and a speed-responsive device 80 subject to the speed of the driven member and operative to vary the effect of said drive means; of reversible electrically actuated adjusting means for adjusting the action of one of said speed responsive devices while 85 running; a rotary commutating device having two contacts of considerable extent individually connected to said adjusting means to control reverse actuations thereof, and driven by one of said driven members; a second rotary commutating device having a single contact of small extent and driven by the other of said driven members; and electric connections connecting the adjusting means and the first commutating device in 90 circuit with the second commutating device, whereby the second commutating device actuates the adjusting means in a direction controlled by the first commutating device according to the direction of phase 95 displacement of the driven members.

3. The combination with two speed controlling mechanisms, each including a driving member, a driven member, a variable magnetic drag device forming the driving 105 connection between said members, and a centrifugal switch for varying the driving action of said magnetic drag device; of reversible electrically actuated adjusting means for adjusting the action of one of said centrifugal switches while running; a rotary commutating device having two contacts of considerable extent individually connected to said adjusting means to control reverse actuations thereof, and driven by one of said driven members; a second rotary commutating device having a single contact of small extent and driven by the other of said driven members; and electric connections connecting the adjusting means and the first 110 commutating device in circuit with the second commutating device, whereby the second commutating device actuates the adjusting means in a direction controlled by the first 115 commutating device according to the direction of phase displacement of the driven members.

4. The combination with two speed controlling mechanisms, each including a driving member, a driven member, a variable 120

5 magnetic drag device forming a driving connection between said members, a centrifugal switch for varying the driving action of said magnetic drag device, and a 10 thermostat operatively related to said centrifugal switch to compensate for local temperature changes; of reversible electrically actuated adjusting means for adjusting the action of one of said centrifugal switches 15 while running; a rotary commutating device having two contacts of considerable extent individually connected to said adjusting means to control reverse actuations thereof, and driven by one of said driven members; a 20 second rotary commutating device having a single contact of small extent and driven by the other of said driven members, and electric connections connecting the adjusting means and the first commutating device in 25 circuit with the second commutating device, whereby the second commutating device actuates the adjusting means in a direction controlled by the first commutating device according to the direction of phase 30 displacement of the driven members.

5. The combination with two speed controlling mechanisms, each including a driving member, a driven member, a variable ratio drive means interposed between said 35 driving and driven members, and a speed responsive device subject to the speed of the driven member and operative to vary the driving ratio of said drive means; of reversible electrically actuated adjusting 40 means for adjusting the action of one of said speed responsive devices while running; a rotary commutating device having two contacts of considerable extent individually connected to said adjusting means to control 45 reverse actuations thereof, and driven by one of said driven members; a second rotary commutating device having a single contact of small extent and driven by the other of said driven members; electric connections 50 connecting the adjusting means and the first commutating device in circuit with the second commutating device, whereby the second commutating device actuates the adjusting means in a direction controlled by the first 55 commutating device according to the direction of phase displacement of the driven members; and manually operable means for effecting a positive adjustment of the angular position of one of said driven members relatively to the other while running, to initiate the desired phase relation.

6. The combination with two speed controlling mechanisms, each including a driving member, a driven member, a variable 60 impositive drive means interposed between said members, and a speed responsive device subject to the speed of the driven member and operative to vary the effect of said drive means; of reversible electrically actuated 65 adjusting means for adjusting the action of

one of said speed responsive devices while running; a rotary commutating device having two contacts of considerable extent individually connected to said adjusting means to control reverse actuations thereof, and driven by one of said driven members; a second rotary commutating device having a single contact of small extent and driven by the other of said driven members; electric connections connecting the adjusting means 70 and the first commutating device in circuit with the second commutating device, whereby the second commutating device actuates the adjusting means in a direction controlled by the first commutating device according to the direction of phase displacement of the driven members; and manually operable means for effecting a positive adjustment of the angular position of one of said driven members relatively to the other 75 while running, to initiate the desired phase relation.

7. The combination with two speed controlling mechanisms, each including a driving member, a driven member, a variable 90 magnetic drag device forming the driving connection between said members, and a centrifugal switch for varying the driving action of said magnetic drag device; of reversible electrically actuated adjusting 95 means for adjusting the action of one of said centrifugal switches while running; a rotary commutating device having two contacts of considerable extent individually connected to said adjusting means to control 100 reverse actuations thereof, and driven by one of said driven members; a second rotary commutating device having a single contact of small extent and driven by the other of said driven members; electric connections 105 connecting the adjusting means and the first commutating device in circuit with the second commutating device, whereby the second commutating device actuates the adjusting means in a direction controlled by the first commutating device according to the direction of phase displacement of the driven members; and manually operable means for effecting a positive adjustment of the angular position of one of said driven members 110 relatively to the other while running, to initiate the desired phase relation.

8. The combination with two speed controlling mechanisms, each including a driving member, a driven member, a variable 120 magnetic drag device forming a driving connection between said members, a centrifugal switch for varying the driving action of said magnetic drag device, and a thermostat operatively related to said centrifugal 125 switch to compensate for local temperature changes; of reversible electrically actuated adjusting means for adjusting the action of one of said centrifugal switches while running; a rotary commutating device having 130

two contacts of considerable extent individually connected to said adjusting means to control reverse actuations thereof, and driven by one of said driven members; a 5 second rotary commutating device having a single contact of small extent and driven by the other of said driven members; electric connections connecting the adjusting means and the first commutating device in circuit 10 with the second commutating device, whereby the second commutating device actuates the adjusting means in a direction controlled by the first commutating device according to the direction of phase displacement of the driven members; and manually 15 operable means for effecting a positive adjustment of the angular position of one of said driven members relatively to the other while running, to initiate the desired phase 20 relation.

9. The combination with two speed controlling mechanisms, each including a driving member, a driven member, a variable ratio drive means interposed between said 25 driving and driven members, and a speed responsive device subject to the speed of the driven member and operative to vary the driving ratio of said drive means; of reversible electrically actuated adjusting 30 means for adjusting the action of one of said speed responsive devices while running; a rotary commutating device having two isolated contacts of considerable extent and a single interposed contact, said two contacts 35 being individually connected to said adjusting means to control the reverse actuations thereof, and said commutating device being driven by one of said driven members; a second rotary commutating device having a 40 single contact of small extent and driven by the other of said driven members; electric connections connecting the adjusting means and the first commutating device in circuit with the second commutating device; a 45 switch controlling said connections; a magnetic actuator for said switch controlled by said interposed contact on said first commutating device; and manually operable means 50 for effecting an initial angular adjustment of one of said driven members with reference to the other while the devices are running.

10. The combination with two speed controlling mechanisms each including a driving member, a driven member, a variable 55 impositive drive means interposed between said members, and a speed responsive device subject to the speed of the driven member and operative to vary the effect of said drive means; of reversible electrically actuated adjusting means for adjusting the action of one of said speed responsive devices while running; a rotary commutating device having two isolated contacts of considerable extent and a single interposed contact, 60 said two contacts being individually con-

nected to said adjusting means to control the reverse actuations thereof, and said commutating device being driven by one of said driven members; a second rotary commutating device having a single contact of small 70 extent and driven by the other of said driven members; electric connections connecting the adjusting means and the first commutating device in circuit with the second commutating device; a switch controlling said 75 connections; a magnetic actuator for said switch controlled by said interposed contact on said first commutating device; and manually operable means for effecting an initial 80 angular adjustment of one of said driven members with reference to the other while the devices are running.

11. The combination with two speed controlling mechanisms, each including a driving member, a driven member, a variable 85 magnetic drag device forming the driving connection between said members, and a centrifugal switch for varying the driving action of said magnetic drag device; of reversible electrically actuated adjusting 90 means for adjusting the action of one of said centrifugal switches while running; a rotary commutating device having two isolated contacts of considerable extent and a single interposed contact, said two contacts 95 being individually connected to said adjusting means to control the reverse actuations thereof, and said commutating device being driven by one of said driven members; a second rotary commutating device having a 100 single contact of small extent and driven by the other of said driven members; electric connections connecting the adjusting means and the first commutating device in circuit with the second commutating device; a 105 switch controlling said connections; a magnetic actuator for said switch controlled by said interposed contact on said first commutating device; and manually operable means 110 for effecting an initial angular adjustment of one of said driven members with reference to the other while the devices are running.

12. A speed regulating device comprising in combination a driving member; a driven member; a variable magnetic drag device forming the driving connection between said members; a centrifugal switch for varying the action of said magnetic drag device; and a thermostat operative upon said centrifugal 115 switch to compensate for the effect of temperature variations.

13. A speed regulating device comprising in combination a driving member; a driven member; a variable ratio drive means interposed between said driving and driven members; a centrifugally actuated device for varying the driving ratio of said drive means; and a thermostat operative upon said centrifugally actuated device to com- 120 125 130

pensate for the effects of temperature variations.

14. A speed regulating device comprising in combination a driving member; a driven member; a variable impositive drive means interposed between said driving and driven members; a centrifugal switch for control-

ling said drive means; and a thermostat operative upon said switch to compensate for the effects of temperature variations.

In testimony whereof I have signed my name to this specification. 10

MELVIN L. SEVERY.
